METHOD OF KNITTING GARMENTS

Harold G. Lacks, New York, N. Y.

Application May 26, 1955, Serial No. 511,190

5 Claims. (Cl. 66—9)

My invention relates to the art of knitting and, more specifically, to knitting on circular, reciprocatingly operable knitting machines.

Objects of my invention are to produce inlaid knittings, that is knittings in which inlay threads are embedded, by reciprocating movement of a circular knitting machine in a quick, efficient and accurate manner, to use the movement of the machine in both directions for laying inlay threads and for engaging the same by knitting threads, to use elastic rubber threads for the inlay, and thereby to produce a highly stretchable knitting.

Other objects are to arrange the feed for the knitting thread so that it follows the feed of the inlay thread during the machine's movement in either direction whereby the following knitting thread can engage the laid inlay thread during the same swing of the machine and in either direction, and the inlay thread is embedded immediately after being laid, thereby to avoid any possibility of misplacement of the inlay thread before it is embedded, and thereby to secure a product of uniform accuracy and free of wrinkles.

Further objects are to make possible the production of an inlaid knitting in which elastic inlay threads extend over the entire width, and thereby to produce a product which is highly stretchable over its entire width.

Still other objects are to make possible a continuous knitting with a single inlay thread and with a single knitting thread, and to attain, with an inlaid knitting, all advantages which the reciprocating knitting on a circular machine has, for example, to attain, with an inlaid knitting, the advantages which are described in the U. S. Patents Nos. 2,511,720 and 2,560,580.

Still further objects are to attain these results on circular, reciprocating knitting machines of standard construction, in a simple and reliable manner and with simple and inexpensive means.

Still other objects and advantages will appear from the following description of the method and of an exemplifying embodiment of my invention, from the appended claims and from the accompanying drawing in which:

Fig. 1 shows a top view of a preferred embodiment of a device for carrying out my invention.

Fig. 2 shows a side view of a portion of the same device, seen in the direction of the arrow 2 in Fig. 1.

Fig. 3 shows a side view of another portion of the same device, seen in the direction of the arrow 3 in Fig. 1.

Fig. 4 shows a perspective view of the same device.

Figs. 5 to 10 show diagrammatically simplified top views of the same device, represented on a smaller scale and showing six different phases of a knitting cycle made according to my invention.

My method comprises the feeding of an inlay thread, preferably of an elastic rubber thread, and of a knitting thread at reciprocatingly turning feed points which are, at least temporarily, shiftable relatively to each other so

2

that the knitting feed can by-pass the inlay feed, and can follow the inlay feed in both turning directions. A more complete description of the method according to my invention will be given later with reference to the shown device. However, it should be noted that this device is only a preferred means for carrying out my invention and that obviously the inventive method can be carried out with various other means. For example, it is not indispensable that the knitting feed follows the inlay feed at the same turning speed as in the shown exemplifying embodiment, but the movements of the two feeds may be co-ordinated in other manner and by other means than in this embodiment.

Referring to the drawings, numeral 4 indicates a rotatable and reciprocatable body which may be a part of a circular knitting machine of known structure and comprises interconnected rings extending about a common vertical axis. The uppermost of these rings indicated by 5 surrounds the circularly arranged and vertically movable needles of the machine. These needles and other well known parts of the machine are not shown in the drawings. The ring 5 is spaced by a gap from the lower ring 6 of the body 4 and is connected with the latter by one or more brackets 7. A stationary ring 8 forms a part of the machine and surrounds the rotatable body 4.

An eyelet 9 is affixed to the ring 5 by a wire 11 which is so bent that the eyelet 9 is positioned close to the outside of the ring 5. A knitting thread 12 of any suitable and known type is supplied to the eyelet 9 in known manner and is fed to the needles through this eyelet which, hence, determines the position of the feed of the knitting thread. The ring 5 may have a recess 13 for friction-free passage of the thread 12.

A guide rail 14 forms a segment of a ring extending concentrically with the body 4 at a distance from the outside of the ring 6. The ends of this sector have about radial extensions 15 affixed to this ring. A block 16 has a channel through which the guide 14 passes slidably so that the block can shift on the guide from one end 15 to the other. In addition to this channel, the block 16 has another, radial channel through which a radially extending bar 17 passes slidably. A tubular piece 18 forms the most central end of the bar 17 and reaches under the lower outer edge of the ring 5. The lower surface of the bar 17 may slidably contact the ring 6. The bar 17 is urged into its innermost position by a spring 19 connecting a pin 21 affixed to the block 16 and a pin 22 affixed to the bar 17.

An inlay thread 23 is fed through the bore of the piece 18 whereby this piece determines the position of the inlay feed. The thread 23 is supplied in well known manner to the piece 18, preferably through an eyelet 24 positioned over the block 16 and affixed to the same by a wire 25.

The inlay feed 18 and the block 16 rotate reciprocatingly together with the guide 14 and the body 4 as long as the block is not prevented from further rotation and thereby is forced to let the guide 14 slide through its channel in the block. This occurs when the block hits one of two stops 26 which are positioned in the rotary path of the block and limit its movement in both rotary directions. The amount of this limitation is defined by the angular distance of the stops which is smaller than the arc corresponding to the total rotation of the body 4.

Each stop 26 is formed by a bolt which has a head facing the path of the block 16 and which passes slidably through a bore of a stationary bracket 27. A spring 28 urges the stop bolt 26 toward the block, but allows some resilient movement in the direction against this urge. The bracket 27 is affixed to a piece 29 which has a downward extension 31 affixed to the stationary ring 8.

Preferably, means are provided for withdrawing the bar 17 with the feed 18 radially outward temporarily when the block is in one of its extreme positions. These means may comprise a pin 32 affixed to the bar 17 and recesses in the stationary pieces 29 which have oblique walls 33 urging the pin 32 outward when this pin enters one of these recesses.

The operation is as follows:

In the phase shown in Fig. 1, the feed 9 and the guide 14 with the block 16, the bar 17 and the feed 18 rotate together in the counter-clockwise direction of the arrow 34. The block 16 is adjacent to the right guide extension 15. The knitting feed 9 follows the inlay feed 18 at an angular distance which is only a small fraction of the total rotation. The knitting thread fed through the feed 9 engages the inlay thread fed through the feed 18 in known manner whereby the inlay thread is embedded in the knitting immediately after having been laid.

When the block 16 reaches the position shown in Fig. 1 in dotted lines, it contacts one of the stops 26 and is stopped after a small compression of the stop spring 28. At the same time, the pin 32 has entered the recess in the piece 29, as shown in dotted lines, and moves along the wall 33 whereby the bar 17 is shifted radially outward and the inlay feed 18 is withdrawn from its feeding position nearest to the needle circle.

Fig. 5 diagrammatically shows the phase in which the block 16 has just come into contact with the stop 26. The inlay feed 18 is not yet withdrawn. The knitting feed 9 moves toward the stopped inlay feed. In this and the following Figs. 6 to 10, the feeds are indicated by little circles, and the threads by radial lines showing the angular positions of the feeds.

Then the knitting feed 9, continuing moving in counter-clockwise direction, approaches the stopped inlay feed 18 while the knitting thread continues engaging and embedding the inlay thread. Then the knitting feed moves beyond the inlay feed. Fig. 6 shows the phase in which the knitting feed has just by-passed the stopped and withdrawn inlay feed. The entire extension of the inlay thread is now engaged by knitting. The mesh-forming knitting may end here whereby the width of the knitted product is equal to the length of the inlay thread. Or the knitting may continue if it is desired to provide the product with a non-stretchable margin extending aside of the elastic width of the product.

While the knitting feed moves relatively to the inlay feed, the guide 14 slides through the channelled block 16. The length of the guide is preferably so dimensioned that the other extension 15 of the guide contacts the block 16 at about the end of the counter-clockwise movement. This contact may occur slightly before the end of this movement whereby the stop 26 is again slightly shifted against the pressure of the spring 28. Hence, the resiliency of the stop has several advantages. It softens the impact of the block at the first contact between block and stop, it allows movement of the guide exactly to the end of the machine's movement and it softens and facilitates the reversal of this movement.

The now returning movement of the machine reverses the movement of the knitting feed into clockwise direction. In the latter direction, the block 16 is not stopped. Hence, the block together with the inlay feed and with the guide takes part in the clockwise movement. Fig. 7 shows a phase shortly after reversal of the rotation of the device. The knitting feed follows the inlay feed now in clockwise direction.

The knitting is resumed as soon as the knitting feed reaches again the angular position in which the mesh-forming knitting ceased during the counter-clockwise movement. In the phase shown in Fig. 8, the device is in the middle of its clockwise swing, the inlay thread being engaged by the following knitting thread. The inlay feed has the same position as in Fig. 1, but is followed

by the knitting feed from the other side. A half cycle of the operation is completed.

The other half cycle corresponds or is symmetric to the first half cycle. The block is stopped by the other stop 26. The knitting feed first approaches and then moves beyond the inlay feed. Fig. 9 shows the phase in which the knitting feed has just by-passed the inlay feed in clockwise direction.

In the phase shown in Fig. 10, the machine has completed its clockwise turn and is just reversing its movement again into counter-clockwise direction. Then, moving in the latter direction, the device reaches the position shown in Fig. 1. A full cycle has been completed, and two rows of inlaid knitting have been made, one row in counter-clockwise and one row in clockwise direction.

Continued operation produces further rows of inlaid knitting in the same manner. The inlay thread forms a coherent zig-zag line embedded in a coherent knitting thread. The knitting needles may be operated in any known and suitable manner, for example so that loops are formed at the ends of the rows whereby the product can be united with another knitting on a looping machine.

I desire it understood that my invention is not confined to the particular manner of operation and to the particular embodiment shown and described, the same being merely illustrative, and that my invention may be carried out in other ways within the scope of the appended claims without departing from the spirit of my invention as it is obvious that the particular manner of operation and embodiment shown and described are only examples of the many ways and means that may be employed to attain the objects of my invention.

For example, while the specification refers to a knitting machine in which the needles do not rotate (a type of circular knitting machine called "revolving cam block machine"), my invention may be as well applied to a knitting machine of the "revolving cylinder" type in which the needles rotate and are operated by a stationary cam block. In this case, the body 4 with the parts affixed to the same and the ring 8 with the parts affixed to the latter must exchange their movability, that is, the body 4 must now be stationary, while the ring 8 rotates reciprocatingly. This mechanical reversal results in the same relative movements of all parts and produces the same effect. I desire it understood, that my claims cover also such a mechanical reversal, and that the movements described in this specification and defined in the appended claims should be regarded rather relatively than absolutely.

Having described the nature of my invention, what I claim and desire to protect by Letters Patent is:

1. A method of producing inlaid knittings; comprising feeding an inlay thread and a knitting thread, each through a separate feed, to a reciprocating circular knitting machine; moving both feeds simultaneously in the same turning direction, the knitting feed following the inlay feed, and the knitting thread engaging the inlay thread; then stopping the movement of said inlay feed while the knitting thread continues engaging the inlay thread as far as the latter is laid; continuing the movement of the knitting feed beyond the stopped inlay feed; then reversing the movement of the knitting feed and starting the inlay feed in the direction of said reversed movement whereby both feeds move again simultaneously and the knitting feed again follows the inlay feed, and again engaging the inlay thread by the knitting thread.

2. A method of producing inlaid knittings, comprising feeding an elastic rubber inlay thread and a knitting thread, each through a separate feed, to a reciprocating circular knitting machine; moving both feeds simultaneously in the same turning direction, the knitting feed following the inlay feed, and the knitting thread engaging the inlay thread; then stopping the movement of said inlay feed while the knitting thread continues engaging the inlay thread as far as the latter is laid; continuing

the movement of the knitting feed beyond the stopped inlay feed; then reversing the movement of the knitting feed and starting the inlay feed in the direction of said reversed movement whereby both feeds move again simultaneously and the knitting feed again follows the inlay feed, and again engaging the inlay thread by the knitting thread.

3. A method of producing inlaid knittings, comprising feeding an inlay thread and a knitting thread, each through a separate feed, to a reciprocating circular knitting machine; moving both feeds simultaneously in the same turning direction, the knitting feed following the inlay feed at the level of the same knitting row, and the knitting thread engaging the inlay thread; then stopping the movement of said inlay feed while the knitting thread continues engaging the inlay thread as far as the latter is laid; continuing the movement of the knitting feed beyond the stopped inlay feed; then reversing the movement of the knitting feed and starting the inlay feed in the direction of said reversed movement whereby both feeds move again simultaneously and the knitting feed again follows the inlay feed, and again engaging the inlay thread by the knitting thread.

4. A method of producing inlaid knittings, comprising feeding an inlay thread and a knitting thread, each through a separate feed, to a reciprocating circular knitting machine; moving both feeds simultaneously in the same turning direction, the knitting feed following the inlay feed at an angular distance which is only a small fraction of the total rotation of the machine, and the knitting thread engaging the inlay thread; then stopping the movement of

said inlay feed while the knitting thread continues engaging the inlay thread as far as the latter is laid; continuing the movement of the knitting feed beyond the stopped inlay feed; then reversing the movement of the knitting feed and starting the inlay feed in the direction of said reversed movement whereby both feeds move again simultaneously and the knitting feed again follows the inlay feed, and again engaging the inlay thread by the knitting thread.

5. A method of producing inlaid knittings, comprising feeding an inlay thread and a knitting thread, each through a separate feed, to a reciprocating circular knitting machine; moving both feeds simultaneously in the same turning direction, the knitting feed following the inlay feed, and the knitting thread engaging the inlay thread; then stopping the movement of said inlay feed while the knitting thread continues engaging the inlay thread as far as the latter is laid, and withdrawing the inlay feed from its feeding position; continuing the movement of the knitting feed beyond the stopped inlay feed; then reversing the movement of the knitting feed, returning the inlay feed to its feeding position and starting the inlay feed in the direction of said reversed movement whereby both feeds move again simultaneously and the knitting feed again follows the inlay feed, and again engaging the inlay thread by the knitting thread.
